UNITED STATES PATENT OFFICE

JOHN L. TOMPKINS, OF CORPUS CHRISTI, TEXAS

VEHICLE PARKING MEANS

Application filed August 23, 1928. Serial No. 301,584.

The invention aims to provide new and improved means whereby automobiles or other vehicles may be taken directly from the traffic lane of a roadway, lowered to a ⁵ subterranean area and returned to the traffic lane without interrupting sidewalk traffic.

In carrying out the above end, an elevator platform is provided normally co-operating with the surface of the street in forming an ¹⁰ uninterrupted traffic surface. This platform is lowered when a machine to be parked is run upon it, and either the actual parking space or a passage leading to said space is transverse to the length of the street, and it ¹⁵ is a further object to provide means whereby the entire platform may be rotated about a vertical axis to permit easy running of the automobile upon said platform into the parking space or passage.

²⁰ A still further aim is to provide a novel, continuous barrier movable upwardly from the elevator shaft for guarding the upper end of said shaft when the elevator platform is to be lowered.

²⁵ Yet another aim is to provide unique locking or supporting means for the elevator platform, automatically releasable by upward projection of the above-named barrier, preventing any possibility of lowering the platform before the barrier is raised.

A still further aim is to make novel provision whereby the platform may be truly horizontal and disposed in convenient relation with the sidewalk and curb, regardless ³⁵ of the usual transverse crown of the street.

With the foregoing and minor objects in view, the invention resides in the novel subject matter hereinafter described and claimed, description being accomplished by reference ⁴⁰ to the accompanying drawings.

Fig. 1 is a perspective view.

Fig. 2 is a vertical longitudinal section on line 2—2 of Fig. 3.

Fig. 3 is a top plan view.

Fig. 4 is a vertical transverse section on line 4—4 of Fig. 3.

Fig. 5 is a horizontal section on line 5—5 of Fig. 4.

Fig. 6 is an enlarged vertical transverse section on line 6—6 of Fig. 2.

Fig. 7 is an enlarged vertical longitudinal section on line 7—7 of Fig. 4.

The general construction and arrangement of parts herein disclosed may be considered as preferred, and while such construction and arrangement will be specifically described, it is to be understood that the present disclosure is primarily for illustrative purposes and that within the scope of the invention as claimed, numerous variations may be made.

The numeral 8 on the drawings denotes a city street, 9 has reference to the sidewalk, and 10 denotes the usual curb. The sidewalk is provided with skylights 11 for illuminating a subterranean parking chamber 12 which is here shown in the form of a passage transverse to the street 8. An elevator shaft 13 is formed from the surface of the street to the passage 12 and the side of said shaft opposite said passage is provided with a niche 14 for a purpose to be described. The wall of this niche is preferably formed on the arc of a circle as seen in Fig. 5 and opposed sides of the shaft 13 adjacent said niche are recessed at 15 on the same arc.

The open upper end of the shaft 13 is near but outwardly spaced a slight extent from the curb 10, and at the inner side of this shaft, an auxiliary curb 16 is provided, parallel with said curb 10, providing a gutter 17 between the two curbs. This gutter is bridged by an appropriate sidewalk extension 18.

The ends of the auxiliary curb 16 are beveled as at 19 to upwardly direct vehicle wheels if striking the same, and in order that the street surface may be truly horizontal at the upper end of the shaft 13, regardless of the transverse crown of said surface, it is gently inclined to the same horizontal plane in which the auxiliary curb 16 and the sidewalk extension 18 are disposed, this inclination being denoted at 19^a. From this inclination, a short ridge 20 extends transversely to the street, being disposed centrally at the outerside of the shaft 13, and this ridge has only a gentle inclination and like the inclination 19^a, merges gradually into the surface of the street to form the least possible ⁹⁰ ⁹⁵ ¹⁰⁰ impediment to the vehicle traffic. Ridge 20

serves to divide water flowing toward the curb from the crown of the street. The inclination 19^a and the auxiliary curb 16 permit the surface of the street at the upper end of the shaft 13 to be substantially flush with the sidewalk 9, and this curb and the sidewalk extension 18, insure an adequate gutter 17 for drainage purposes.

A horizontal elevator platform 21 is provided in the shaft 13 and is normally flush with the upper portions of the street surface inclinations 19^a, so that said platform and the surface of the street may co-operate in providing an uninterrupted traffic lane. A car 10 to be parked, is run upon the platform 21 and occupants wishing to alight, may pass across the sidewalk extension 18 to the sidewalk 9. Pedestrians upon this sidewalk are protected against injury, for instance from a machine skidding as it comes to rest upon the platform, by appropriate posts 22. After any occupants so desiring have left the machine, a continuous barrier 23 is elevated to the position shown in Fig. 1 to guard the upper end of the shaft 13, said barrier being normally confined in said shaft. Upon raising of the barrier, the platform 21 may be lowered, and the mounting of this platform is such that it may be turned about a vertical axis, as shown in dotted lines in Figs. 4 and 5 when in its lowered position, the niche 14 and the recesses 15 serving to prevent the platform or the machine thereon from striking any part of the shaft wall. When the machine has been run into the chamber or passage 12, the platform 21 may be turned to its normal position with respect to the shaft 13 and again raised, after which the barrier 23 is lowered. The entire mechanism is of course operated by an attendant having controls at any desired locations.

In the present showing, the platform 21 is carried by the upper end of a plunger 24 which is slidable and rotatable in a cylinder 45 disposed at the lower end of the shaft 13 and extending to the necessary depth, said plunger being hydraulically operated or controlled by other fluid under pressure. This is not only a safe and efficient means for lowering and raising the platform 21, but also constitutes a pivot upon which the entire platform may be swung from one position to the other.

Appropriate guides 26 are shown at the four corners of the shaft 13 and may be stationarily mounted in any desired manner. The corners of the platform 21 normally engage the guides 26 but these guides terminate above the plane occupied by the upper surface of the platform when the latter is lowered, as seen in Fig. 4. Hence, maximum lowering of the platform causes it to clear the guides 26 and it is then free to be swung by hand or power as occasion may demand. The lower ends of the guides are outwardly

curved as at 27 to assist in re-engaging the platform 21 with them, when said platform is righted and again elevated.

The barrier 23 is in the nature of a continuous fence and while it may be operated in any desired way, I have shown it provided with plungers 28 extending into fluid pressure cylinders 29. At the upper end of this barrier, is a continuous horizontal frame 30 having downturned flanges 31 and 32 at its inner and outer edges. Continuous grooves 33 and 34 are formed in the upper side of the platform 21 and in the street surface around the shaft 13, respectively, and these grooves snugly receive the flanges 31—32 when the barrier 23 is lowered, at which time the frame 30 is substantially flush with the top of the platform.

Interlocking cogs are provided for effectively holding the platform 21 in raised position, these cogs and associated parts being most clearly illustrated in Fig. 6.

Gears 40 are rotatably mounted in supports 41 secured in the top of the shaft 13 below the grooves 33 and 34. These gears engage with racks 42 secured to the edges of the platform 21 and similar racks 43 secured to the frame 30 between the flanges 31 and 32. When the platform 21 is in its position at the upper limit of its travel and the barrier 23 is in its lowered position, the gears 40 are meshed with the racks 42 and 43 and the platform is effectively held in raised position.

Self-projecting safety chocks 35 are provided for effectively guarding the platform 21 against accidental falling. These chocks and associated parts being most clearly illustrated in Figs. 6 and 7. Each chock 35 is pivoted at 36 in a recess 37 in a side of the shaft 13, near the upper end of the latter, and the body portions of these chocks are so offset with respect to the pivots 36 as to cause swinging of said chocks into the shaft, as shown in Fig. 7, when such swinging is permitted. The barrier 23, in the present disclosure, embodies certain horizontal bars 38 and vertical plates 39 extending downwardly from said bars. When the barrier is raised as seen for instance in Fig. 2, the plates 39 hold the chocks 35 in retracted position, as also illustrated in this view. Upon lowering of the guard 23 however, the chocks 35 swing inwardly over the bars 38, in which positions they are inwardly inclined. Thus, these chocks effectively support the platform 21 and this platform cannot be lowered until the chocks are released. Moreover, these chocks cannot be so released until the barrier 23 is raised. Upon raising of this barrier, the bars 39 outwardly swing and thus release the chocks 35, and the plates 39 hold said chocks released as long as the barrier remains raised.

The end of the barrier 23 which faces oncoming traffic when raised, may be provided with an appropriate red light or the like to

be distinctly visible when raised. At 44 in Fig. 1, I have indicated rays of light projected from this danger signal, and it may be considered that the latter is inset in any appropriate part of the barrier 23.

Attention is again invited to the fact that the present disclosure is primarily for illustrative purposes. Hence, it is to be understood that within the scope of the invention as claimed, numerous variations may be made.

I claim:—

1. In combination with a roadway; an elevator shaft whose upper end opens through the surface of said roadway, an elevator platform movable in said shaft and normally co-operable with the roadway surface in providing an uninterrupted traffic lane, a subterranean area transverse to said street communicating with the lower end of said shaft, means under said platform for lowering and raising the same and allowing turning of the lowered platform for alinement with said area, and a barrier upwardly shiftable from the shaft for guarding the upper end of said shaft when said platform is lowered.

2. In combination with a roadway, a sidewalk and a curb between roadway and sidewalk, an elevator shaft opening through the surface of the roadway near but outwardly spaced from the curb, an auxiliary curb at the inner side of said shaft disposed in parallel relation with the first mentioned curb, a sidewalk extension spanning the space between said two curbs, an elevator platform movable in said shaft and in its normal position substantially flush with said sidewalk extension, the roadway surface adjacent to said shaft being gently inclined to the normal plane of said platform whereby the latter normally co-acts with said roadway surface in providing an uninterrupted traffic lane, a subterranean area transverse to said street communicating with the lower end of said shaft, means under said platform for lowering and raising the same and allowing turning of the lowered platform for alinement with said area, and a barrier upwardly shiftable from the shaft for guarding the upper end of said shaft when the platform is lowered.

3. In combination with a roadway; an elevator shaft whose upper end opens through the surface of said roadway, an elevator platform movable in said shaft and normally co-operable with the roadway surface in providing an uninterrupted traffic lane, a subterranean area transverse to said roadway and communicating with the lower end of said shaft, an elevating and lowering power unit at the lower end of the shaft connected with said platform for lowering and raising the same, a barrier movable upwardly from the shaft for guarding the same when the said platform is lowered, and a pivot about which

the platform is swingable to permit alinement of said platform with said subterranean area.

4. In combination with a roadway; an elevator shaft whose upper end opens through the surface of said roadway, an elevator platform movable in said shaft and normally co-operable with the roadway surface in providing an uninterrupted traffic lane, a subterranean area communicating with the lower end of said shaft, means under said platform for lowering and raising the same, and a barrier upwardly shiftable from the shaft for guarding the upper end of said shaft when said platform is lowered.

5. In combination with a roadway, a sidewalk and a curb between roadway and sidewalk, an elevator shaft opening through the surface of the roadway near but outwardly spaced from the curb, an auxiliary curb at the inner side of said shaft disposed in parallel relation with the first mentioned curb, a sidewalk extension spanning the space between said two curbs, an elevator platform movable in said shaft and in its normal position substantially flush with said sidewalk extension, the roadway surface adjacent to said shaft being gently inclined to the normal plane of said platform whereby the latter normally co-acts with said roadway surface in providing an uninterrupted traffic lane, a subterranean area communicating with the lower end of said shaft, means under said platform for lowering and raising the same, and a barrier upwardly shiftable from the shaft for guarding the upper end of said shaft when the platform is lowered.

In testimony whereof I have hereunto affixed my signature.

JOHN L. TOMPKINS.
